[57] **CLAIM**

The ornamental design for a combined turbine exhaust vent and vent hatch cover, as shown and described.

DESCRIPTION

FIG. 1 is a perspective view of the design; FIG. 2 is a perspective view of the design installed on the roof of a recreational vehicle; FIG. 3 is an exploded view of the design as shown in FIG. 1; FIG. 4 is a top plan view of the design as shown in FIG. 1; FIG. 5 is a bottom plan view of the design as shown in FIG. 1; FIG. 6 is a front elevational view of the design as shown in FIG. 1; FIG. 7 is a rear elevational view of the design as shown in FIG. 1; FIG. 8 is a right side elevational view of the design as shown in FIG. 1; and, FIG. 9 is a left side elevational view of the design as shown in FIG. 1. The broken line showing of environmental structure in FIGS. 2 and 3 is for illustrative purposes only and forms no part of the claimed design.
